W. C. NOBLE & B. W. CORSON.
SECTIONAL BARREL.
APPLICATION FILED JULY 1, 1916.

1,278,495.

Patented Sept. 10, 1918.

UNITED STATES PATENT OFFICE.

WILLIAM C. NOBLE AND BLAKE W. CORSON, OF RICHMOND, VIRGINIA.

SECTIONAL BARREL.

1,278,495.

Specification of Letters Patent. Patented Sept. 10, 1918.

Application filed July 1, 1916. Serial No. 107,013.

To all whom it may concern:

Be it known that we, WILLIAM C. NOBLE and BLAKE W. CORSON, citizens of the United States, and both residing at Richmond, in 5 the county of Henrico and State of Virginia, have invented certain new and useful Improvements in Sectional Barrels, of which the following is a specification.

This invention relates to certain novel and 10 useful improvements in barrels, casks, hogsheads and similar receptacles.

In the following description we have referred to the invention as embodied in the form of a sectional barrel, and where we employ the term barrel, we wish it to be understood as including casks, tierces, hogsheads and other similar receptacles or retainers.

In the present instance it is our purpose 20 to provide a barrel composed of a plurality of parts or sections which are adapted to be assembled to form a complete container these sections being capable of being readily disassembled or dismantled when desired, and when so dismantled they may be nested or 25 packed so as to save space or room in storage and also to reduce the expense ordinarily incident to the shipment or transportation of empty barrels.

Still a further object of our invention is 30 the provision of a sectional barrel equipped with locking or fastening devices by means of which the barrel sections may not only be united or connected in assembled condition, but these locking or fastening devices also 35 serve to draw the abutting faces or edges of the barrel sections into a relatively close engagement thereby insuring tight joints or seams, so that the entrance of an excessive amount of air and moisture into the barrel 40 through the joints or seams is prevented, and consequently the contents of the barrel, especially when of a perishable nature, will be protected against deterioration due to atmospheric influences.

Another object of our invention is the provision of a barrel of this class which is so equipped with locking or fastening devices 45 for uniting the sections that when the members of each fastening device are arranged in a coöperative or interlocking relation, the barrel sections will be maintained in their proper position relative to each other so that movement of the barrel sections, relative to each other will be prevented.

Furthermore we propose to provide a sec-

tional barrel wherein the heads, constituting the top and bottom portions of the barrel may be readily and quickly placed and locked in assembled position in the body of the barrel or unlocked and removed therefrom as occasion may warrant. 60

With the above recited objects and others of similar nature in view, our invention consists in the construction, combination and arrangement of parts set forth in and falling 65 within the scope of the appended claims.

In the accompanying drawing:

Fig. 1 is a side elevation of a barrel embodying the invention, a portion of the barrel being broken away to show one of the 70 locking or fastening devices for a head of the barrel.

Fig. 2 is a bottom plan view showing the bottom head of the barrel in its locked or assembled position. 75

Fig. 3 is an enlarged detail view in elevation of one of the locking or fastening members for uniting the barrel sections.

Fig. 4 is a horizontal view taken on the line 4—4 of Fig. 1. 80

Fig. 5 is a cross sectional view taken on the line 5—5 of Fig. 2.

Fig. 6 is a view showing the barrel sections as they appear when taken down and nested or packed for shipment or storage. 85

Fig. 7 is a view of the bottom portion of a barrel partially broken away to show the bottom head of the barrel as supported on hoops.

Referring now to the accompanying drawing in detail the letters A and B indicate the two sections constituting the body of the barrel, while the top head or cover thereof is indicated at C and the bottom head is shown at C'. In the present instance we 90 have shown the body of the barrel as composed of but two parts or sections, but it will of course be understood that it may be made up of any number of sections. The individual sections are formed in any of the 100 well-known ways, each section carrying its individual hoops or bands, as at 1, secured to the sections in suitable manner as by rivets or screws 2. The ends of the hoops terminate at the longitudinal edges 3 of the 105 sections, so that when the two sections are assembled, as shown in Fig. 1, with the longitudinal or meeting edges of the sections in abutment or contact, the ends of the hoops of one barrel section will substantially abut 110

against the ends of the adjacent hoop of the other barrel section.

In order to unite or connect the two barrel sections A and B in the assembled position shown in Figs. 1 and 2 we employ a series of locking or fastening devices, each of which is indicated as an entirety by the letter D, and as these fastening devices are all similar in construction and operation, a 10 description of one will suffice for all.

Each locking or fastening device D comprises a latching member E and keeper member F as best shown in Figs. 3 and 4. Each latching member E preferably comprises a 15 metallic strap 4 which gradually widens toward one end, said strap being adapted to be secured to the barrel section by means of rivets or screws 5, the widened end of this latching member E, which is the end 20 nearest the longitudinal edge of the barrel section is bent outward or off-set as shown at 6, and is provided with a notch 7 for a purpose hereinafter mentioned.

Pivoted to this off-set end 6, as at 8, are 25 the spaced parallel plates 9, having a latching bolt 10, passing transversely therethrough. The keeper member F, in the present instance, comprises a strap 11 fastened to the opposite barrel section from that 30 carrying the latching member E, the securing means for the keeper strap being in the nature of rivets, screws or the like, shown at 12. This strap 11 also widens toward the longitudinal edge of the barrel section 35 to which it is attached, and is off-set as at 13, the off-set end of this strap 11 lying in substantially the same plane as the off-set end 6 of the strap 4. The off-set portion 13 of the keeper strap is provided with an 40 open segmental slot 14 which is adapted to receive and retain the latching bolt 10, while one end of the off-set portion 13 of the keeper strap is provided with a wedge-shaped or tapered tongue 15 which is 45 adapted to fit into the correspondingly wedge-shaped or tapered notch 7 of the strap member 4, as is clearly shown in Fig. 3.

From the above description it will be seen that when the two barrel sections A and 50 B are assembled, as shown in Fig. 1, the tongue 15 of the keeper strap will fit into the notch 7 of the alining or adjacent latching strap and thus the two barrel sections will be locked against relative movement in 55 the direction of the longitudinal axis of the barrel. The latching plates 9 may now be swung upon the pivot 8 to bring the latching bolt 10 into the keeper slot 14 and as this slot varies from a true arc inscribed 60 with bolt 8 as the center, the inward movement of the latching bolt in the slot acts to draw the ends of the strap closer together and consequently the closer the meeting edges 3 of the barrel sections will be brought 65 into contact or abutment. Furthermore it

will be noted that when the latching plates 9 are swung to bring the bolt 10 into the slot 14 these latching plates 9 will lie at opposite sides of the meeting ends of the two straps and consequently lateral movement and accidental disengagement of the straps will be prevented by these plates 9. Of course we may employ any suitable number of these locking devices, for instance six preferably arranged in opposing pairs 75 at the bottom, the middle and the top of the barrel body.

The heads C and C' of our sectional barrel are also capable of being connected to and disconnected from the body section of the 80 barrel suitable fasteners being employed for this purpose. We may employ any desired number of these fasteners which are shown at G, and as all these fasteners are alike in construction, a description of one 85 will be sufficient.

Referring especially to Figs. 2 and 5, the numeral 16 indicates a supporting plate which is fastened to a barrel head by suitable screws, rivets or the like shown at 17, the 90 outer edge of this plate being preferably curved or rounded as at 18 to correspond to the curvature of the periphery of the head. A screw shank 19 is carried by this plate and projects through an elongated slot 20 in 95 a sliding bolt 21. This bolt 21 is preferably in the nature of a flat strip or plate the inner end of which is turned up as at 22 to form a finger grip. A suitable nut 23 and a washer 24 are employed for the purpose of 100 retaining the bolt in its proper sliding position on the supporting plate 16. The opposite end portion 25 of this bolt is adapted to be projected through a locking slot 26 cut in the chime 27 of the barrel, this plate also 105 passing through an alining slot 28 in the chime hoop of the barrel and thence through a slot 29 in a small plate 30 riveted to the hoop. It will be noted that when the sliding bolts or plates 21 are shifted outward the 110 proper distance they will be projected through the alining keeper slots therefor as above described, and the head thus securely retained in position relative to the body of the barrel, the sliding movement of each 115 sliding bolt being of course limited by the end walls of the slot 20 striking the screw shank 19.

From the above description taken in connection with the accompanying drawing the 120 construction and manner of employing our invention will be readily apparent. The two sections A and B of the body of the barrel are first assembled and locked or united by means of the locking devices, heretofore described, and the barrel is then filled with the produce such as tobacco or the like. After the barrel has been filled the head is placed in position and fastened by means of its fasteners as heretofore mentioned.

It will be noted that the produce may be tightly packed within the barrel by exerting suitable pressure upon the head to force the latter downward into the barrel body thus, 5 at the same time bringing the head into proper position so that the sliding bolts of the fasteners G may be projected through the slots intended to receive the same.

In order to dismantle the barrel it is only 10 necessary to release the locking devices of the body section of the barrel and the fasteners for the heads thereof, so that the barrel may be taken down, and the sections then nested as shown in Fig. 6. One head then 15 may be superposed on the other so that the entire barrel may be compactly stored in a relatively small space.

We wish it to be further understood that if desired either or both of the heads may be 20 fastened to the body of the barrel by other means than those shown herein. For instance referring to the modification shown in Fig. 7, the head C' of the barrel is shown as resting upon and supported by a pair of 25 hoops, as shown at 1', it will of course be understood that in the case of the sectional barrel, each hoop of the pair 1' is made up of two semi-circular sections, which may be secured to the body of the barrel at the inner 30 wall thereof, in any suitable manner. Furthermore if desired one head may be provided with the fastening device shown in Figs. 1 to 5 inclusive, while the other head may rest upon the inner hoops or the like.

35 While we have herein shown and described one particular embodiment of our invention, we wish it to be understood that we do not confine ourselves to all the precise details of construction herein set forth by way of illustration, as modification and variation may be made without departing from the spirit of the invention or exceeding the scope of the appended claims.

What we claim is

45 1. A barrel including a body portion comprising a plurality of separable sections having edges adapted to be placed in abutting relation, and means for detachably securing a section against lateral movements and for 50 drawing the abutting edges of the sections into close contact and maintaining the same in such position, said means including a keeper member carried by one of said sections and provided with a segmental latch- 55 receiving portion, and a coöperating latching member pivotally connected with an adjacent section and movable to engage the latch-receiving portion, said latching member being adapted to extend on opposite sides 60 of the keeper member when in engagement.

2. A barrel including a body portion comprising a plurality of separable sections having edges adapted to be placed in abutting relation, and means for detachably securing 65 a section against lateral movements and for

drawing the abutting edges of the sections into close contact and maintaining the same in such position, said means including a keeper member carried by one section and provided with a segmental latch-receiving slot, and a coöperating latching member carried by an adjacent section and having a latching bolt adapted to be received by and retained in the slot of the keeper member, 70 said latching member being adapted to extend on opposite sides of the keeper member when the latching bolt is engaged.

3. A barrel including a body portion comprising a plurality of separable sections having edges adapted to be placed in abutting relation, and means for detachably securing a section against lateral movements and for drawing the abutting edges of the sections into close contact and maintaining the same in such position, said means including a 80 keeper member attached to one section and having an off-set end provided with a latch-receiving portion, a latching member carried by an adjacent section and also having an off-set end, and a latch carried by the last 85 said off-set end and adapted to be moved into and retained by the latch-receiving portion of the keeper member, said latching member extending on opposite sides of the keeper member when the latch is positioned in the 90 keeper member.

4. A barrel including a body portion comprising a plurality of separable sections having edges adapted to be placed in abutting relation, and means for detachably securing the sections together against relative movement and for drawing the abutting edges of the sections into close contact and maintaining the same in such position, said means including a strap-like member attached to 100 one section and provided with a latch-receiving portion, and a second strap-like member attached to an adjacent section and provided with a pivoted latch adapted to be swung into engagement with and held by the latch-receiving portion of the first mentioned strap-like member, said strap-like members having inter-engaging ends.

5. A barrel including a body portion comprising a plurality of separable sections having edges adapted to be placed in abutting relation, and means for detachably securing a section against lateral movements and for drawing the abutting edges of the sections into close contact and maintaining the same 115 in such position, said means including a strap-like member attached to one section and provided with an off-set end portion having a bolt receiving slot therein, and a second strap-like member attached to an adjacent section and having an off-set end portion and a pair of spaced plates pivoted to 120 said off-set end portion and carrying a locking bolt adapted to be moved into and retained in the slot of the first mentioned 125

130

strap-like member, said plates extending on opposite sides of the said latter member when the bolt is in such slot.

6. A barrel including a body portion comprising a plurality of separable sections having edges adapted to be placed in abutting relation, and means for detachably securing the sections together against relative movement and for drawing the abutting edges of the sections into close contact and maintaining the same in such position, said means including a strap-like member attached to one section and provided with an off-set end portion having a bolt receiving slot therein, and a second strap-like member attached to an adjacent section and having an off-set end portion and a pair of spaced plates pivoted to said off-set end portion and carrying a locking bolt adapted to be moved into and retained in the slot of the first mentioned strap-like member, one of said strap-like members having a tongue adapted to fit in a notch formed in the other strap-like member

to hold said strap-like members against relative endwise movement. 25

7. A sectional barrel comprising a plurality of separable sections having edges adapted to be placed in abutting relation, and means carried by adjacent sections for detachably securing abutting edges together 30 against relative movement, said means including members carried by the sections and having mating ends adapted to prevent relative endwise movement of the edges, one of said members carrying a latching device 35 engageable with the other section and extending over the opposite sides of said member mating ends when engaged to prevent relative transverse movements of the edges.

In testimony whereof we affix our signatures in the presence of two witnesses.
